UNITED STATES PATENT OFFICE

ARNOLD H. GOSS, OF DETROIT, MICHIGAN

MECHANICAL REFRIGERATION

Application filed June 3, 1926. Serial No. 113,422.

My invention relates to mechanical refrigeration, and particularly to mechanical refrigeration units of the self-contained type, and the principal object of my invention is to provide a new and improved unit of this type. In the drawings accompanying this specification and forming a part of this application I have shown, for purposes of illustration, one form which my invention may 10 assume. In these drawings:

Figure 1 is a front elevation of the embodiment of my invention herein shown and described,

Figure 2 is a view similar to Figure 1 but 15 with the doors open exposing the interior,

Figure 3 is a section on the line 3—3 of Figure 1, while

Figure 4 is a fragmentary detail on the line 4—4 of Figure 1.

20 The embodiment of my invention herein shown comprises a refrigerator cabinet 11 divided into a refrigeration compartment 12 and a compressor compartment 13 and comprising a shield 14 having a wing 15 arranged 25 to separate the refrigeration compartment 12 into a refrigerating section 16 and a refrigerated section 17 separated except for convection openings at the top and bottom, and having also a wing 18 integral with the wing 15 and closing the front of the refrigerating section 16 except for an opening 19 arranged 30 to provide access through the wing 18 to receptacles 20 for the formation of artificial ice, the receptacles 20 being supported by

35 suitable cleats 21 secured to the walls of an aperture 22 formed in a brine tank 23 positioned within the refrigerating section 16 to provide refrigeration of the refrigeration compartment 12 and itself refrigerated by 40 means of an expansion coil (not shown) contained therein and having its inlet 24 connected to an expansion valve 25 and its outlet 26 connected to end turns 27 encircling a thermostat 28 provided with a thermostatic 45 switch 29.

Mounted within the compressor compartment 13 is an electric motor 30 having one terminal connected directly to the line conductor 31 and the other terminal connected 50 to the line conductor 32 through an inter-

mediate conductor 33 and the thermostatic switch 29, and operating by means of a belt 34 a compressor 35 also disposed within the compressor compartment 13 having its inlet connected by means of a duct 36 to the end 55 turns 27, and having its outlet connected by means of a duct 37 to the inlet of a condenser 38 also disposed within the compressor compartment 13 and having its outlet connected by means of a duct 39 to the expansion 60 valve 25.

Within the refrigerator section 17 I have shown shelves 40 arranged to carry the material to be refrigerated and supported in position by means of cleats 41 secured on one 65 side to the wall of the refrigerator cabinet 11 and on the other side to the wing 15 of the shield 14.

In the embodiment of my invention herein shown I provide access to the compressor 70 compartment 13 by means of an opening 42 arranged to be closed by means of a suitable door 43, and to the refrigeration compartment 12 by means of an opening 44 affording access at all times to the ice receptacles 20 and the refrigerated section 17 and, upon removal of the shield 14, to the entire refrigerating apparatus including the brine tank 23 and the expansion valve 25 and the thermostat 28, and in the embodiment of my invention herein 75 shown I provide a single door 45 arranged to close the entire opening 44, consisting of an inner wall 46 and an outer wall 47 spaced from each other, and carrying between the inner wall 46 and outer wall 47 a combination 80 lock 48 operable by means of a knob 49 disposed on the exterior face of the door 45 and including a bolt 50 arranged to prevent rotation of a disc 51 carried by a shaft 52 and provided with cam slots 53 in which ride pins 54 carried by bolts 55 and 56 and 57 arranged 85 to seat within the side and top and bottom walls respectively of the opening 44 to lock the door 45 in position closing the aperture 44 until the bolts 55 and 56 and 57 are withdrawn by rotation of the disc 51 permitted by the lock 48 and effected through the shaft 52 by means of a handle 58 positioned on the end of the shaft 52 exteriorly of the door 45. 90 95 100

From the above description it will be obvious to those skilled in the art that I have provided mechanical refrigeration means wherein the expansion means and the control means and the ice means and the refrigerating section and the refrigerated section and the material within the refrigerated section are all accessible through a single opening, provided with a single door for closing this opening, and provided on this door with a lock disposed within the walls of the door out of communication with the refrigeration compartment and arranged to lock the door closed to thus prevent access to the expansion means and the control means and the ice means and the refrigerating section and the refrigerated section and the material within the refrigerated section.

At the same time it will also be obvious to those skilled in the art that the particular embodiment of my invention herein shown and described may be variously changed and modified without departing from the spirit of my invention or sacrificing the advantages thereof and it will therefore be understood that the disclosure herein is illustrative only and that my invention is not limited thereto.

I claim:

In a refrigerated cabinet, a frame formed of walls arranged to define a single refrigerated chamber, one wall of said frame having an opening extending substantially the entire height and width of said chamber, a single door closing the opening in said wall, a shield having an aperture therethrough and arranged to divide said chamber into two compartments extending the entire depth and height thereof, said shield having top and bottom openings therethrough to permit circulation of air between said compartments, and a freezing unit in one of said compartments provided with freezing trays so disposed as to be accessible through the opening in said frame and the aperture in said shield.

In testimony whereof I hereunto affix my signature.

ARNOLD H. GOSS.
